UNITED STATES PATENT OFFICE.

EDWARD C. NEWCOMB, OF NORTH SCITUATE, MASSACHUSETTS, ASSIGNOR OF ONE-HALF TO GEORGE F. CHAMBERLIN, OF NEW YORK, N. Y.

APPARATUS FOR GENERATING STEAM.

981,218.

Specification of Letters Patent. Patented Jan. 10, 1911.

Application filed May 18, 1908. Serial No. 433,342.

To all whom it may concern:

Be it known that I, EDWARD C. NEWCOMB, a citizen of the United States, and a resident of North Scituate, county of Plymouth, and 5 Commonwealth of Massachusetts, have invented certain new and useful Improvements in Apparatus for Generating Steam, of which the following is a specification.

My invention relates to the generation of 10 steam or other vapor, and more particularly to apparatus which in whole or in part may be employed for carrying out the inventions set forth in United States Letters Patent No. 704,907 and No. 704,908, both dated July 15 15, 1902.

In accordance with the preferred embodiments of my present improvements and as set forth in the patents referred to, the generation of the steam is such that the thermal 20 energy thereof is varied in substantial unison with the variations of demand for such energy and in substantially the same degree with said variations of demand, so that little reserve energy is required in the apparatus, 25 and yet the steam is delivered in a substantially predetermined condition as to temperature and pressure, irrespective of the variations of demand. This is accomplished by varying the supplies of the water or 30 other fluid to be vaporized and the fuel for heating the same in substantial unison with the variations of demand for the thermal energy contained in the steam or other vapor and each according to definite quantitative 35 relations to said variations of demand, as more fully set forth in the patents referred to.

As shown and described in the patents referred to, the means for supplying the water 40 and fuel are operated or controlled by an engine driven by the steam delivered from the generator, the supplies being controlled independently of the speed of the engine.

An object of my present improvements is 45 to provide means for supplying water to the generator and fuel to the burner for heating the generator, which means are self-contained and controlled independently of an engine or other apparatus by which the 50 steam delivered from the generator is utilized. This and other objects will in part be obvious and in part be more fully set forth in the following description.

A preferred embodiment of my present

improvements comprises a burner, a generator having a continuous passage arranged to receive the water at one end and to deliver steam at the other end, a pump for supplying fuel to the burner, a pump for supplying water to the generator, a motor for driving said pumps, and means rendered operative by variations in the condition of the fluid at a predetermined point in the generator passage for controlling said pump. 55

In accordance with some features of the 65 present improvements, means other than a pump may be employed for supplying the fuel, and any suitable means provided for effecting and controlling the supply of fuel to the burner, such, for example, as a means 70 of the character set forth in the patents referred to. In accordance with certain features of the present improvements, moreover, any suitable form of generator may be employed, and the pump driving motor may 75 be controlled by variations in the condition, either as to pressure, temperature, or density, of the fluid in the generator or of the steam generated therein, depending on the character of the generator and the desired 80 qualities of the steam generated. In accordance with the preferred embodiment, however, the generator is constructed of coiled pipe forming a single continuous passage arranged with relation to the combustion chamber so that different parts of the generator are heated to different temperatures, the water being supplied to a cooler part so that it is gradually heated to the 85 temperature of vaporization, gradually vaporized, and the steam superheated and delivered from a hotter portion of the generator. 90

Where a generator of the preferred type 95 is employed, to-wit, one having a continuous passage arranged to receive water at one end and to deliver steam at the other end, the pump driving motor is preferably controlled through a relatively wide range of duty by a relatively slight range of variations in the 100 controlling condition of the fluid in the generator so that the condition of the generator will remain substantially uniform and the supplies of both the fuel and water be varied in substantial unison with the variations of 105 demand for the thermal energy of the steam or other vapor delivered from the generator and according to substantially definite quan-

titative relations to said variations of demand. Preferably, the condition, either as to pressure, temperature or density, of the fluid in that part of the generator wherein the water is vaporized is employed as the controlling condition, as any variation in the quantity of water in the generator or of the distribution of the heat in the generator is necessarily accompanied by a variation of the condition of the fluid in the part of the generator referred to. If the condition of the fluid in this part of the generator is maintained substantially uniform, the condition of the generator will remain substantially uniform. In order that the steam may be delivered from the generator at a desired or predetermined temperature and pressure, means are provided whereby the relation between the supplies of the water and the fuel may be varied. Furthermore, where the efficiency of the apparatus, viz., the mean efficiency of the generator and burner, varies with different loads or demands for the thermal energy of the steam, means may be provided for automatically varying the relation between the supplies of the water and the fuel to compensate for such variations of efficiency. In carrying out this feature the variations in the temperature of the generator or of the fluid therein at any point where the temperature varies with the variations of efficiency may be utilized for automatically varying the relation between the supplies of the water and the fuel.

In accordance with a preferred embodiment of the present improvements, the pump driving motor is a steam motor connected with the generator. In order that this motor may act with the desired promptness, it is preferably in constant communication with the generator and is controlled by means acting upon one of the valves by which the steam is distributed therein, as required to produce the movements thereof; and, where the condition of the fluid as to pressure is utilized for controlling the motor, the latter is, for the sake of simplicity of construction and operation, made to communicate with that part of the generator where the variations of pressure are to be utilized, and the motor is controlled by means acting on the steam distributing valve, said means being rendered operative by the variations in the pressure upon the valve.

While any suitable fuel supply means may be used whereby the supply of fuel may be accurately regulated and quickly varied, a liquid fuel which may be supplied to a suitable burner by a pump is preferably employed. It is to be understood also that any suitable liquid other than water may be supplied to the generator.

65 For the sake of brevity, I have herein re-

ferred to the variations of the thermal energy of the steam or other vapor delivered by the apparatus as variations of demand for steam energy.

It is not to be understood by the expression "substantial unison", as used herein that the relative variations between the demands for the supplies of the fluids are strictly simultaneous. The essential in this regard is that the variations be produced with sufficient promptness to maintain the apparatus in a practically predetermined condition. For instance, the pumps and motor for supplying the fuel and water are preferably capacitated to supply the same at a greater rate than is required by the demand, and said parts are operated intermittently, the mean supplies of the fluids being varied by the variations of the frequency or duration of the operations of the pumps or by variations of both the frequency and the duration of such operations.

The expressions "substantially in definite quantitative relation" and, "substantially in predetermined quantitative relation", as used herein, are not to be understood as necessarily referring to unchanging relations between the supplies of the fuel and water on the one hand and the demand for steam energy on the other hand, for such relations may be made to vary. It is intended that these expressions shall comprehend such relations between the supplies of the fluids and the demand as will produce practically uniform results and maintain the apparatus in a practically predetermined condition. Where, for example, the efficiency of the apparatus varies materially with different demands for steam energy, the definite or predetermined relations between the supply of the water and the fuel may be so changed as to compensate for variations in the efficiency of the apparatus and to deliver the steam at the desired temperature and pressure at all times.

My present invention consists in the novel improvement, combinations, and constructions herein shown and described.

The accompanying drawings, which are referred to herein and form a part hereof, illustrate one embodiment of my invention together with certain modifications thereof, the same serving in connection with the description to explain the principles of the invention.

Of the drawings, Figure 1 is a view, partly in section and partly in elevation, illustrating an apparatus constructed in accordance with certain features of the invention; Fig. 2 is a front elevation, partly in section, of the pumps and pump-operating motor for supplying water and fuel to the apparatus, and also part of a form of means for controlling the motor; Fig. 3 is a vertical section of the same taken on the line 3—3 of Fig. 2; Fig. 4

is a plan view of the pumps; Fig. 5 is a vertical section illustrating certain details of the water pump, the section being taken on the line 5—5 of Fig. 4; and Fig. 6 is a view 5 similar to Fig. 1, illustrating certain modifications and additional features of the apparatus.

While some of the advantages of my invention may be realized by the use of various 10 forms of generators, the best results can only be obtained in connection with the main features of my improvements by the use of a generator having a continuous passage in which the water is gradually heated from its 15 point of entrance until it is brought to the temperature of vaporization and is then gradually vaporized, only a small quantity of the liquid in the generator being maintained at the temperature of vaporization 20 corresponding to the pressure at which the apparatus is operated.

In accordance with the particular embodiment of the invention illustrated, the generator is constructed of coiled pipe forming a 25 single continuous passage adapted to receive the water at one end and to deliver the steam in a superheated condition at the other end.

As shown, the generator consists of six 30 frusto-conical pipe coils numbered 1, 2, 3, 4, 5, and 6, said coils being nested one within another and all being of substantially the same diameter at the larger end but successively longer from the outer coil to the inner coil so as to form an approximately cylindrical mass of heating surfaces. The coils are connected in series, as by suitable 35 connections 7, 8, 9, 10, and 11. The coils surround the combustion chamber and the convolutions of the coils are suitably 40 separated from each other so as to provide passages for the flow of the products of combustion throughout the entire mass of heating surfaces from the inner coil to the outer coil, suitable shields 12 and 13 being 45 provided so as to cause all the products of combustion to pass between the convolutions of each of the coils successively from the innermost coil to the outermost coil. The outermost coil is projected outwardly at its 50 lower end and is connected to the supply pipe 15, and the innermost coil is projected outwardly at its lower end and is connected to the steam delivery pipe 16 so that the fluid is caused to flow from the outermost 55 coil to the innermost coil in a general direction opposite to that in which the flow of the products of combustion takes place, whereby the heat of the products of combustion is efficiently absorbed and the fluid is 60 gradually heated from the point of entrance to the point of delivery. The total area of the passages for the products of combustion between the convolution of each coil is successively decreased from the innermost coil 65 to the outermost coil to correspond substan-

tially with the decrease in the volume of the products of combustion due to the decrease in the temperature thereof. By reason of this construction the efficiency of the generator is high and the products of combustion 70 are caused to flow in substantially the same path at all times, so that the distribution of the heat in the generator remains practically uniform irrespective of variations of load. This generator is substantially like the generator described in the patents hereinbefore referred to and will operate as described in 75 said patents. The generator is preferably incased in a substantially cylindrical casing 17, between the lower part of which and the shield 12 is formed an annular discharge flue 80 for the waste products of combustion.

Any suitable means may be provided to effect the combustion of the fuel. As shown, the burner comprises a perforated plate 18, 85 between which and a plate 19 is provided a chamber adapted to receive a suitable mixture of fuel and air from a central mixing tube 20 and evenly distribute this mixture throughout the area of the perforated plate 90 18. As shown, the mixing tube 20 is vertically arranged and extended upwardly through the center of the space inclosed by the generator coils through the center of the top plate 21 of the generator casing. To 95 evenly distribute the mixture, a distributing plate 22 is preferably arranged between the plates 18 and 19, said plate 22 being connected to the lower end of the mixing tube 20 and separated a suitable distance from the plate 19 at its outer edge. Liquid fuel is supplied through a pipe 23 to a vaporizing coil 24 arranged above the burner, the vaporized fuel being led by a pipe 25 to a nozzle 26 arranged in the mouth of the mixing tube 20. For the purpose of heating the fuel vaporizer to start the burner, a suitable pilot burner is provided. As shown, the pilot burner consists of a hollow member 27 having a vaporizing passage in its lower end to which a suitable liquid fuel is supplied by a pipe 27^a and from which the vaporized fuel is led through a nozzle regulated by a needle valve 28 to the combustion chamber in the member 27. The air necessary to 115 support the combustion is supplied through perforations in the member 27, as shown. The pilot burner is protected by a suitable perforated casing 29, having a cup-shaped lower end adapted to receive a small quantity of alcohol or gasoline to start the burner. The pilot burner is designed to operate continuously to form an igniter for the main burner so that the latter is permitted to become extinguished when there is no demand for steam from the generator. The vaporizer 24 of the main burner is preferably formed of small tubing having ample heating surface and a small quantity of reserve energy so that the heat developed by 120 125 130

the burner will vary in substantial unison with the variations in the supply of fuel to the vaporizer. The mixing tube 20 is preferably shielded from the heat of the combustion chamber by a tube 30, between which and the tube 20 a packing of refractory material may be provided. As shown, the generator coils are supported by a casting 31 which rests upon the base ring 32 carried by suitable brackets, one of which is illustrated at 33.

As regards some features of the invention, the water may be supplied to the generator by any suitable form of pump, and this pump may be driven by any form of motor the operation of which may be promptly varied through a wide range of duty, and the fuel may be supplied by any means adapted to maintain a predetermined relation between the supplies of fuel and water. As shown, the water is supplied to the generator by a pump 34, and the fuel is supplied to the burner by a pump 35. These pumps may be of the single acting plunger type, as shown, the water pump having a reciprocating plunger 36 and suitable suction and delivery valves 37 and 38, respectively, as clearly shown in Fig. 5, and the fuel pump having a reciprocating plunger 39 and suction and delivery valves 40 and 41, respectively, as shown in Fig. 2. The plungers of the water and fuel pumps are provided with suitable stuffing boxes 42 and 43, respectively, and the plungers 36 and 39 are caused to reciprocate in unison by an arm 44 fixed on the plunger 36 and arranged to embrace the plunger 39. The desired predetermined relation between the supplies of water and fuel may be obtained by making the areas of the two plungers 36 and 39 proportionate to the desired relation between the volumes of the water and the fuel, respectively, and driving both plungers the same length of stroke. Preferably, however, the area of the fuel plunger is made slightly greater than that indicated, and the stroke of the pump made correspondingly shorter than the stroke of the fuel pump, as by providing a suitable amount of lost motion between the fuel plunger and its operating arm 44; and in order that the effective displacement of the fuel plunger may be varied with relation to the displacement of the water plunger, means are provided whereby the lost motion between the fuel plunger and the arm 44 may be varied. As shown, the plunger 39 is provided with a pair of collars or projections 45 and 46 between which the arm 44 plays with the desired lost motion, the amount of which may be varied by varying the distance between the said collars. As shown, the collar 46 is in the form of a pair of lock nuts threaded on the lower end of the plunger.

65 The pumps may be connected to and

driven by the motor in any suitable way. As shown, a steam motor is provided, the same including a single acting piston 47 mounted in a cylinder 48 and having a piston rod 49 arranged in line with the plunger 36 of the water pump. It will be understood that for the sake of clearness in the drawing the pumps and motor are drawn to a larger scale than the generator as represented in Fig. 1. As actually constructed, 75 the pumps and motor are about three-fifths the size shown in proportion to the size of the generator as shown, and the generator is constructed of three-quarter inch seamless steel tubing.

80 The steam may be admitted to and discharged from the power cylinder 48 of the motor by any suitable form of steam-distributing valve mechanism adapted to produce the required movements of the piston. 85 Preferably and as shown, steam admission and exhaust valves 50 and 51, respectively, are provided, the same consisting of reciprocating valves of the puppet type normally pressed toward their seats by light springs, 90 one of which is shown on the drawing at 52. As shown, these valves are arranged in a steam chest 53 secured at one side of the power cylinder 48 and communicating therewith through a port 54. The valves may be alternately opened and closed by any suitable mechanism operated by the reciprocation of the steam piston or of parts moving therewith. As shown, the distributing valves 50 and 51 are operated by stems 55 and 56, respectively, said stems projecting upwardly through perforations in the valve chest 53 and arranged to be acted upon by the opposite ends of a lever 57 pivotally mounted at an intermediate point on a fulcrum post adjustably secured on the steam chest 53. The lever 57 is oscillated by a rod 58 pivotally connected to the lever 57 and passing through an arm 59 fixed on the arm 44. The motions of the arm 59 are communicated in each direction to the rod 58 by means of springs 60 and 61 arranged on the rod 58 on the opposite sides of the arm 59. In order that the tension of these springs may be varied, adjusting nuts 60^a and 61^a are provided for the respective springs 60 and 61. Steam is admitted to the pump beneath the valve 50 through a pipe 62, and the steam is exhausted through the valve 51 and may be delivered at any desired point through the exhaust pipe 63. It will be seen that by suitably tensioning the springs 60 and 61, the valves 50 and 51 will be alternately opened and closed as the parts reach or approach the opposite ends of their strokes so that the piston will be alternately driven upward and allowed to descend, as required to operate the pumps. While the motor may be made double acting, as by duplicating the valve mechanism described, 130

it is preferred to make it single acting and cause the downward or idle stroke thereof together with the suction strokes of the two pumps by a spring or springs. As shown, 5 two tension springs 64 and 65 are provided, the same being arranged between suitable supports at the lower end of the supporting frame 66 of the pump structure and a cross-arm 67 fixed on the lower end of the water 10 plunger 36.

In order that the pumps may be operated by hand, as required to start the apparatus, a suitable hand lever 68 is provided, the same, as shown, being pivoted on the supporting frame 66 and having an arm 69 adapted to engage a shoulder or ledge 70 on the hub of the crossarm 67.

While the pump-driving motor may be controlled in various ways, preferably and 15 as shown, it is controlled by one of the steam distributing valves 50 and 51. To this end the condition as to pressure of the steam in the generator is utilized to control the motor, and the motor is connected by the pipe 20 62 to a predetermined point in the generator, to-wit, that part of the generator, the variations of the pressure in which are to be utilized to control the motor. As before 25 pointed out, it is preferred to control the motor by variations in the condition of the fluid in or near that part of the generator wherein the vaporization of the water takes place. In order that the steam supplied to the motor may be adapted to efficiently 30 operate the motor, it is preferred to connect the same to a part of the generator which is approximately at the end of the vaporizing portion of the generator; or, if the connection is made to the vaporizing portion at a 35 point where water is not all vaporized, the connecting pipe may be passed through the combustion chamber so as to complete the vaporization and dry or superheat the steam before it reaches the motor. As shown, the 40 pipe 62 communicates with the connection 11 between the innermost coils 5 and 6 of the generator, it having been found in practice that with a generator constructed as shown and described the point indicated will be 45 near the limit of that part of the generator in which the vaporization takes place under normal conditions. If desired, the pipe 62 may be extended through the combustion 50 chamber in order to thoroughly dry or superheat the steam before it is delivered to the pump.

In the embodiment of the invention illustrated the pump is preferably in normal communication with the generator, and the 55 variations of the pressure in that part of the generator with which the pump is in communication may be rendered effective to control the pump through either one of the steam distributing valves. Assuming 60 that the parts are in the position shown in

Fig. 2, it will be seen that the valve 50 is held to its seat by the pressure of the steam in addition to the light pressure of the spring 52 and that this pressure is opposed by the compression of the spring 60. The 70 steam pressure has access to the lower part of this valve 50 through a small opening in the side thereof (shown at the left of Fig. 2) which communicates with the recess in which the spring 52 is located and also 75 through the small annular passage formed by the loose fit of the valve 50 in its socket. When the pressure of the steam falls so that the force acting upon the valve is less than the force exerted by the spring 60, the 80 valve will open and admit steam to the power cylinder so as to drive the motor piston 47 upward. This pressure will also be transmitted to the under side of the valve 85 51 through the opening in the side thereof, as explained in connection with valve 50, and will act together with the spring under that valve to hold it to its seat, these forces also acting through the stems 55 and 56 and lever 57 to hold the valve 50 off its seat. 90 As the parts approach the upper limit of their stroke, the spring 61 will be put under compression and this spring may be so adjusted that it will force the valve 51 off its seat even though the pressure of the steam 95 be greater than it was when the valve was opened. The opening of the valve 51 will permit the closing of the valve 50 so that the steam will be shut off from the cylinder and the steam in the cylinder will be permitted to escape through the valve 51 so that the piston together with the pump plungers may be returned by the springs 64 and 65. If the water and fuel supplied to the generator 100 and burner, respectively, by a single operation of the pumps serve to raise the pressure in the generator sufficiently to prevent the opening of the valve 50, the motor will remain at rest, when the parts return, until the pressure in the generator again drops 105 below the point predetermined by the adjustment of the tension of the spring 60. It will be seen that by suitably adjusting the springs 60 and 61, the operation of the motor may be controlled by the variations of 110 pressure acting upon either or both the valves 50 and 51. It is found in practice that this device is extremely sensitive, the operation of the motor being controlled through its maximum range of duty by a 115 very slight range of variations in pressure of the steam admitted to the motor.

The speed at which the motor operates may be controlled in any desired manner. The power stroke may be regulated by suitably restricting the flow of the water from the water pump to the generator, as by means of the valve 15^a in the water supply pipe. The speed of this stroke of the pump may also be controlled by restricting the 120 130

flow of the steam to the pump, as by means of the valve 62^a in the pipe by which the motor is connected to the generator. The speed of the return stroke of the motor and pumps may also be controlled by any suitable means, as by restricting the passage through which the steam is exhausted from the power cylinder. Preferably, this restriction is located in the port 54 at a point 10 between the power cylinder and the exhaust valve, as by providing a restricting valve 54^a in said port. If this restriction should be located so that the back pressure produced in the power cylinder were communicated to the top of the valve 50, such pressure would tend to open said valve and thereby interfere with the accurate control of the motor. By having the motor in constant communication with the generator, it 20 is kept in a heated condition and the steam, when admitted to the power cylinder, will be immediately effective to cause the prompt operation of the motor.

In accordance with the construction 25 illustrated in Fig. 6, the fuel pump plunger 39^a is connected with the water pump plunger by a lever 44^a pivoted at an intermediate point so that when the water pump plunger is making its displacement or supply stroke, the fuel pump plunger is making its return or suction stroke, and vice versa. By reason of this construction the return stroke of the water pump and motor may 30 be controlled by the pressure developed in the vaporizer of the burner, which pressure would depend upon and never exceed that due to the tension of the spring which effects said return movement. In this way the pressure in the fuel vaporizer is automatically limited and may be determined so that the burner will always operate at the desired capacity and cannot be operated at a higher capacity or be overloaded. With this construction also the valves and passages 35 by which the steam is admitted to and discharged from the power cylinder may be made as large as required to secure a prompt action of the motor even if there should be an accumulation of water in the power cylinder. In this construction the return stroke of the pump is effected by a spring 40 connected with the lever 44^a, and the latter is provided with a handle 72 by which the pumps may be operated by hand, as required for starting the apparatus. If desired, the apparatus may be started or heated up by supplying fuel to the burner without supplying water to the generator. To 50 this end the fuel pump plunger is provided with a handle 73 whereby the fuel pump may be operated by hand without operating the water pump. As shown, the handle 73 is pivoted to the plunger 39^a at a point above the end of the lever 44^a and carries 55 the adjustable collar 46^a whereby the stroke

of the pump may be varied, so that when the handle is swung up to the horizontal position, the fuel pump is disconnected from the lever 44^a and may be operated independently of the water pump. The handle 73 70 may be secured in its horizontal position by a pin passing through a hole in the handle and a corresponding hole or holes in a lateral extension of the collar 45^a on the plunger 39^a. The motor, including the 75 steam-distributing valves, of this construction is the same as that illustrated in Figs. 1, 2, and 3. As shown in Fig. 6, however, the springs 60 and 61 are represented so adjusted that the exhaust valve 51 is utilized 80 to effect the control of the motor, the power cylinder being normally in communication with the generator. With this arrangement it will be observed that each supply of fuel to the burner always precedes the corresponding supply of water to the generator, the restoration of the normal condition of the generator being thereby more promptly effected.

Where the efficiency of the apparatus varies for any reason, as with variations of load, the predetermined relation between the supplies of fuel and water which the pumps tend to maintain may be automatically varied in numerous ways, as by means acting to control the effective delivery of either or both the pumps, said means being rendered operative by variations in some condition of the generator or the fluid therein, which result from variations in the efficiency 95 of the apparatus.

In accordance with one feature of the invention and as shown, the effective delivery of the fuel pump is controlled by means acting intermittently to prevent the suction valve from seating, thereby permitting a charge of fuel to be returned to the fuel supply instead of being delivered to the burner. As shown, a pin 75 is arranged above the suction valve 40 of the fuel pump, 100 said pin projecting through the pump casing where it is adapted to be engaged by a set screw 76 adjustably fixed on a lever 77 pivoted on the casing and connected by its short arm 78 with one end of a Bourdon tube 79 115 rigidly fixed at its other end to the pump casing. The Bourdon tube may be connected to any predetermined point in the generator, the condition of the fluid in which varies with a variation in the efficiency of either the 120 generator or the burner or of both members, and is not subject to substantial fluctuations by reason of temporary or abnormal conditions, as by sudden changes of load. As shown, the Bourdon tube is connected 125 by a capillary pipe 80 with a vapor tension thermostat 83 located at a point in advance of the vaporizing portion of the boiler, as in the union 9 between the generator coils 3 and 4. The thermostat might be located 130

beyond the vaporizing portion but, where the apparatus is subjected to great fluctuations of demand, it should not be located so near the end of the vaporizing portion that its temperature will be increased sufficiently to operate the thermostat whenever the demand for steam is suddenly increased, as an increase in the flow of the steam through the superheater will cause an increase in temperature independent of a change in the temperature of the superheater. With the arrangement shown the capacity of the fuel pump is so adjusted with relation to the water pump that the steam will be heated to the desired temperature under the conditions prevailing when the apparatus is least efficient. When these conditions change so that the efficiency of the apparatus increases, the temperature of the thermostat will be increased and the supply of fuel will be reduced, the Bourdon tube being rendered operative by the variations in the condition as to temperature of the fluid at that point in the generator passage at which the thermostat is located to vary the effective supply of fuel as required to maintain the apparatus in a substantially uniform condition. The normal condition of the apparatus can be varied or predetermined by means of the set screw 76.

It is obvious that another form of thermostat and connections may be used and that by means of a suitable thermostat and connections the variations in temperature of the desired part of the generator, or of the fluid therein, might be used instead of the pressure to control the motor, as by controlling the admission of the steam thereto or the distribution of the steam therein. In either case the motor will be controlled through a wide range of duty by a relatively slight range of variations in the controlling condition. The motor will act therefore to maintain the condition of the generator or the fluid therein at the point from which the motor is controlled substantially uniform. In order to maintain the generator in a uniform condition, the motor should be controlled from a point in the generator such that, if the controlling condition which is utilized to control the motor is kept uniform at that point, the apparatus will remain in a uniform condition. I have found that the generator will remain in substantially uniform condition if the pressure or the temperature of the fluid in or near that part of the generator where the water is vaporized under normal conditions be kept uniform. In that the temperature and the pressure of the fluid at this part of the generator bear a predetermined relation to each other either the temperature or the pressure may be utilized; and, furthermore, in that the temperature of this part of the generator must be substantially the same as

that of the fluid therein contained, the temperature of this part of the generator itself may be utilized with the same result. In view of the fact that the motor, acting through the fuel and water pumps, will tend to maintain that part of the apparatus from which it is controlled in a substantially uniform condition irrespective of variations in efficiency of the apparatus, the means for automatically varying the relation between the supplies of fuel and water to compensate for variations in efficiency should be controlled from some other point of the generator. It is more desirable to utilize the variations of temperature at some point in the water heating portion of the generator rather than at some point in the superheating portion, as the temperature of the water heating portion is not as subject to abnormal fluctuations due to temporary changes of conditions, as a sudden increase in the demand for steam energy, as is the latter portion. If the variations of the demand for steam energy are not too sudden or do not vary through too wide a range, good results may be secured by utilizing the temperature or the pressure at other points of the generator for controlling the supplies of water and fuel and the relation between said supplies.

It is to be understood that my invention in its broader aspects is not limited to the particular construction shown, nor to any particular construction by which it has been or may be carried into effect, as the construction of the apparatus may be greatly varied without departing from the main principles of the invention and without sacrificing its chief advantages.

I claim:

1. An apparatus for generating steam including in combination, a burner; a generator having a continuous passage constructed to receive water at one end and to deliver steam at the other end, a pump for supplying fuel to the burner, a pump for supplying water to the generator, a motor for simultaneously driving said pumps, and means rendered operative by a relatively slight range of variations in the condition of the fluid at a predetermined point in the generator passage for controlling said motor through a relatively wide range of duty, whereby the supplies of both the fuel and the water are varied in substantial unison with the variations of demand for steam energy and in a definite quantitative relation to said variations of demand.

2. An apparatus for generating steam including in combination, a burner, a generator having a continuous passage constructed to receive water at one end and to deliver steam at the other end, a pump for supplying fuel to the burner, a pump for supplying water to the generator, a motor

for simultaneously driving said pumps, and means rendered operative by a slight range of variations in the condition of the fluid at or near that part of the generator passage where the water is vaporized for controlling said motor through a relatively wide range of duty, whereby the supplies of both the fuel and the water are varied in substantial unison with the variations of demand for steam energy and in a definite quantitative relation to said variations of demand.

3. An apparatus for generating steam including in combination, a burner, a generator having a continuous passage constructed to receive water at one end and to deliver steam at the other end, a pump for supplying fuel to the burner, a pump for supplying water to the generator, a motor for simultaneously driving said pumps, and means rendered operative by a slight range of variations in the pressure of the fluid at or near that part of the generator passage where the water is vaporized for controlling said motor through a relatively wide range of duty, whereby the supplies of both the fuel and the water are varied in substantial unison with the variations of demand for steam energy and in a definite quantitative relation to said variations of demand.

4. An apparatus for generating steam including in combination, a burner, a pump for supplying fuel to the burner, a generator consisting of coiled pipe arranged with relation to the burner so that different portions are heated to different temperatures, a pump for supplying water to a cooler part of the generator, a motor for simultaneously driving said pumps, and means rendered operative by a relatively slight range of variations in the condition of the fluid at a hotter part of the generator for controlling said motor through a relatively wide range of duty, whereby the supplies of both the fuel and the water are varied in substantial unison with the variations of demand for steam energy and in a definite quantitative relation to said variations of demand.

5. An apparatus for generating steam including in combination, a burner, a pump for supplying fuel to the burner, a generator consisting of coiled pipe arranged with relation to the burner so that different portions are heated to different temperatures, a pump for supplying water to the generator, a motor for simultaneously driving said pumps, and means rendered operative by a relatively slight range of variations in the condition of the fluid at or near that part of the generator where the water is vaporized for controlling said motor through a relatively wide range of duty, whereby the supplies of both the fuel and the water are varied in substantial unison with the variations of demand for steam energy and in a definite quantitative relation to said variations of demand.

definite quantitative relation to said variations of demand.

6. An apparatus for generating steam including in combination, a burner, a pump for supplying fuel to the burner, a generator consisting of coiled pipe arranged with relation to the burner so that different portions are heated to different temperatures, a pump for supplying water to a cooler portion of the generator, a motor for simultaneously driving both said pumps, and means rendered operative by a relatively slight range of variations in the pressure at or near that part of the generator where the water is vaporized for controlling said motor through a relatively wide range of duty, whereby the supplies of both the fuel and the water are varied in substantial unison with the variations of demand for steam energy and in a predetermined quantitative relation to said variations of demand.

7. An apparatus for generating steam including in combination, a burner, means for supplying fuel to the burner, a generator having a continuous passage arranged to receive water at one end and to deliver steam at the other end, a pump for supplying water to the generator, a motor for driving said pump, means rendered operative by a relatively slight range of variations in the condition of the fluid at a predetermined point in the generator passage for controlling said motor through a relatively wide range of duty, and means for maintaining a substantially predetermined quantitative relation between the supplies of the water and fuel, whereby the supplies of both the water and the fuel are varied in substantial unison with the variations of demand for steam energy and in a definite quantitative relation to said variations of demand.

8. An apparatus for generating steam including in combination, a burner, means for supplying fuel to the burner, a generator having a continuous passage arranged to receive water at one end and to deliver steam at the other end, a pump for supplying water to the generator, a motor for driving said pump, means rendered operative by a relatively slight range of variations in the condition of the fluid at a predetermined point in the generator passage for controlling said motor through a relatively wide range of duty, means tending to maintain a substantially predetermined quantitative relation between the supplies of the fuel and the water, and means for automatically varying said relation, whereby the supplies of both the fuel and the water are varied in substantial unison with the variations of demand for steam energy, and in a substantially predetermined quantitative relation to said variations of demand.

9. An apparatus for generating steam including in combination, a burner, means for

supplying fuel to the burner, a generator having a continuous passage arranged to receive water at one end and to deliver steam at the other end, a pump for supplying water 5 to the generator, a motor for driving said pump, means rendered operative by a relatively slight range of variations in the condition of the fluid at one point in the generator passage for controlling said motor 10 through a relatively wide range of duty, means tending to maintain a substantially predetermined quantitative relation between the supplies of fuel and water, and means rendered operative by variations in the condition of the fluid at another point of the 15 generator passage for varying the relation between said supplies.

10. An apparatus for generating super-heated steam including in combination, a burner, means for supplying fuel to the burner, a generator consisting of coiled pipe arranged with relation to the burner so that the water is gradually heated to the temperature of vaporization, gradually vaporized and then superheated, a pump for supplying water to the generator, a motor for driving said pump, means rendered operative by a relatively slight range of variations in the pressure of the fluid at or near 20 that part of the generator where the water is vaporized for controlling said motor through a relatively wide range of duty, means tending to maintain a substantially predetermined quantitative relation between 25 the supplies of fuel and water, and means rendered operative by variations in the temperature of the fluid at another part of the generator for varying the relation between 30 said supplies.

40 11. An apparatus for generating steam including in combination, a burner, a generator having a continuous passage arranged to receive water at one end and to deliver steam at the other end, a pump for supplying fuel
45 to the burner, a pump for supplying water to the generator, a motor for driving said pumps, and means rendered operative by variations in the condition of the fluid at a predetermined point in the generator for
50 controlling said motor.

12. An apparatus for generating steam including in combination, a burner; a generator having a continuous passage arranged to receive water at one end and to deliver steam at the other end, a pump for supplying fuel to the burner, a pump for supplying water to the generator, a motor for driving said pumps, and means rendered operative by a relatively slight range of variations in the condition of the fluid at a predetermined point in the generator passage for controlling said motor through a relatively wide range of duty.

65 13. An apparatus for generating steam including in combination, a burner, a gener-

ator having a continuous passage arranged to receive water at one end and to deliver steam at the other end, a pump for supplying fuel to the burner, a pump for supplying water to the generator, a motor for driving said pumps, and means rendered operative by a relatively slight range of variations in the pressure of the fluid at or near that part of the generator where the water is vaporized for controlling said motor through a relatively wide range of duty. 70 75

14. An apparatus for generating steam including in combination; a burner, a generator having a continuous passage arranged to receive water at one end and to deliver steam at the other end, a pump for supplying fuel to the burner, a pump for supplying water to the generator, a steam pump connected with the generator for driving said pumps, and means rendered operative by a relatively slight range of variations in the condition of the fluid at a predetermined point in the generator passage for controlling said motor.

15. An apparatus for generating steam 90 including in combination, a burner, a generator having a continuous passage arranged to receive water at one end and to deliver steam at the other end, a pump for supplying fuel to the burner, a pump for supplying water to the generator, a steam motor connected with the generator for driving said pumps, and means rendered operative by a relatively slight range of variations in the pressure of the fluid at or near that 95 part of the generator where the water is vaporized for controlling said motor through a relatively wide range of duty. 100

16. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pumps, means rendered operative by variations in the condition of the fluid at a predetermined point in the generator passage for controlling said motor, and means for varying the relation between the effective deliveries of said pumps. 110 115

17. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pump, means rendered operative by variations in the condition of the fluid at a predetermined point in the generator passage for controlling said motor, and means for varying the effective delivery of said fuel pump. 120 125 130

18. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pumps, means rendered operative by variations in the condition of the fluid at a predetermined point in the generator passage for controlling said motor, and means for automatically varying the relation between the effective deliveries of said pumps. 5
19. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pump, means rendered operative by variations in the condition of the fluid at a predetermined point in the generator passage for controlling said motor, and means for automatically varying the effective delivery of said fuel pump. 10
20. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pumps, means rendered operative by variations in the condition of the fluid at a predetermined point in the generator passage for controlling said motor, and means for automatically varying the effective delivery of said fuel pump. 15
21. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pumps, means rendered operative by variations in one condition of the fluid in the generator for controlling said motor, and means rendered operative by another condition of the fluid in the generator for varying the relation between the effective deliveries of said pumps. 20
22. An apparatus for generating steam including in combination, a burner, a generator having a continuous passage arranged to receive water at one end and to deliver steam at the other end, a pump for supplying fuel to the burner, a pump for supplying water to the generator, a motor for simultaneously driving said pumps, means rendered operative by variations in one condition of the fluid in the generator for controlling said motor, and means rendered operative by variations in another condition of the fluid in the generator for varying the effective delivery of the fuel pump. 25
23. An apparatus for generating steam including in combination, a burner, a generator having a continuous passage arranged to receive water at one end and to deliver steam at the other end, a pump for supplying fuel to the burner, a pump for supplying water to the generator, a motor for driving said pumps, means rendered operative by variations in the pressure of the steam for controlling said motor, and means rendered operative by variations in the temperature of the fluid at a predetermined point in the generator passage for varying the effective delivery of the fuel pump. 30
24. An apparatus for generating steam including in combination, a burner, a generator having a continuous passage arranged to receive water at one end and to deliver steam at the other end, a pump for supplying fuel to the burner, a pump for supplying water to the generator, a motor for driving said pumps, means rendered operative by variations in the condition of the fluid at one point in the generator passage for controlling said motor, and means rendered operative by variations in the condition of the fluid at or near another point of the generator passage for varying the relation between the effective deliveries of said pumps. 35
25. An apparatus for generating steam including in combination, a generator having a continuous passage arranged to receive water at one end and to deliver steam at the other end, a pump for supplying water to the generator, a motor for driving said pump, and means rendered operative by variations in the condition of the fluid at a predetermined point in the generator passage for controlling said motor. 40
26. An apparatus for generating steam including in combination, a generator having a continuous passage arranged to receive water at one end and to deliver steam at the other end, a pump for supplying water to the generator, a motor for driving said pump, and means rendered operative by a relatively slight range of variations in the condition of the fluid at a predetermined point in the generator passage for controlling said motor through a relatively wide range of duty. 45
27. An apparatus for generating steam including in combination, a generator having a continuous passage arranged to receive water at one end and to deliver steam at the other end, a pump for supplying water to the generator, a motor for driving said pump, and means rendered operative by a relatively slight range of variations in the condition of the fluid at or near that point in the generator passage for controlling said motor. 50

part of the generator where the water is vaporized for controlling said motor through a relatively wide range of duty.

28. An apparatus for generating steam including in combination, a generator having a continuous passage arranged to receive water at one end and to deliver steam at the other end, a pump for supplying water to the generator, a motor for driving said pump, and means rendered operative by a relatively slight range of variations in the pressure of the steam at or near that part of the generator where the water is vaporized for controlling said motor through a relatively wide range of duty.

29. An apparatus for generating steam including in combination, a generator, a pump for supplying water to the generator, a steam motor for driving said pump, said motor including a steam distributing valve and being in constant communication with the generator, and means acting on said distributing valve and rendered operative by variations in the condition of the steam to control said motor.

30. An apparatus for generating steam including in combination, a generator, a pump for supplying water to the generator, a steam motor for driving said pump, said motor including a steam distributing valve and being in constant communication with the generator, and means acting on said steam distributing valve and rendered operative by variations in the pressure of the steam supplied to the motor for controlling the motor.

31. An apparatus for generating steam including in combination, a generator, a pump for supplying water to the generator, a steam motor for driving said pump, said motor including a steam distributing valve and being in constant communication with a predetermined point in the generator, and means acting on said steam distributing valve and rendered operative by variations in the pressure of the steam admitted to the motor for controlling the motor.

32. An apparatus for generating steam including in combination, a generator, a pump for supplying water to the generator, a steam motor for driving said pump, said motor including a power cylinder in normal communication with the generator and a valve for exhausting the steam from said cylinder, and means acting on the said exhaust valve and rendered operative by variations in the condition of the steam in the generator for controlling said motor.

33. An apparatus for generating steam including in combination, a generator, a pump for supplying water to the generator, a steam motor for driving said pump, said motor having a power cylinder normally in communication with the generator and a valve for exhausting the steam from said

cylinder, and means acting on said exhaust valve and rendered operative by variations in the pressure in the power cylinder for controlling said motor.

34. An apparatus for generating steam including in combination, a generator having a continuous passage arranged to receive water at one end and to deliver steam at the other end, a pump for supplying water to the generator, a steam motor for driving said pump, said motor including a power cylinder in constant communication with a predetermined point in the generator and a valve for exhausting the steam from said cylinder, and means acting on said exhaust valve and rendered operative by the pressure in the power cylinder for controlling said motor.

35. An apparatus for generating steam including in combination, a generator having a continuous passage arranged to receive water at one end and to deliver steam at the other end, a pump for supplying water to said generator, a steam motor for driving said pump, said motor including a power cylinder normally in communication with that part of the generator in which the water is vaporized and a valve for exhausting the steam from said cylinder, and means acting on said exhaust valve and rendered operative by variations in the pressure in the power cylinder for controlling said motor.

36. An apparatus for generating steam including in combination, a burner, a generator, a pump for supplying fuel to the burner, a pump for supplying water to the generator, a steam motor for driving said pumps, said motor including a steam distributing valve and being in constant communication with the generator, and means acting on said distributing valve and rendered operative by variations in the condition of the fluid in the generator for controlling said motor.

37. An apparatus for generating superheated steam including in combination, a burner, a generator having a continuous passage arranged to receive water at one end gradually heat and vaporize it, superheat it and deliver the superheated steam at the other end, a pump for supplying fuel to the burner, a pump for supplying water to the generator, a motor for driving said pumps, and means rendered operative by variations in the condition of the fluid at a predetermined point in the generator passage for controlling said motor.

38. An apparatus for generating superheated steam including in combination, a burner, a generator having a continuous passage arranged to receive water at one end gradually heat and vaporize it, superheat it and deliver the superheated steam at the other end, a pump for supplying fuel

to the burner, a pump for supplying water to the generator, a motor for driving said pumps, and means rendered operative by a relatively slight range of variations in the 5 condition of the fluid at a predetermined point in the generator passage for controlling said motor through a relatively wide range of duty.

39. An apparatus for generating super-
10 heated steam including in combination, a burner, a generator having a continuous passage arranged to receive water at one end gradually heat and vaporize it, super-heat it and deliver the superheated steam
15 at the other end, a pump for supplying fuel to the burner, a pump for supplying water to the generator, a motor for driving said pumps, and means rendered operative by a relatively slight range of variations in the 20 condition of the fluid at or near that part of the generator where the water is vaporized for controlling said motor through a relatively wide range of duty.

40. An apparatus for generating super-
25 heated steam including in combination, a burner, a generator having a continuous passage arranged to receive water at one end gradually heat and vaporize it, super-heat it and deliver the superheated steam
30 at the other end, a pump for supplying fuel to the burner, a pump for supplying water to the generator, a motor for driving said pumps, and means rendered operative by a relatively slight range of variations in the 35 pressure of the steam at or near that part of the generator where the water is vaporized for controlling said motor through a relatively wide range of duty.

41. An apparatus for generating steam
40 including in combination, a burner, a generator, a pump for supplying fuel to the burner, a pump for supplying water to the generator, a steam motor for driving said pumps, said motor including a steam dis-
45 tributing valve and being in constant com-
munication with the generator, and means acting on said distributing valve and rendered operative by variations in the condition of the steam to control said motor.

42. An apparatus for generating steam
50 including in combination, a burner, a generator, a pump for supplying fuel to the burner, a pump for supplying water to the generator, a steam motor for driving said pumps, said motor including a steam dis-
55 tributing valve and being in constant com-
munication with the generator, and means acting on said steam distributing valve and rendered operative by variations in the pres-
60 sure of the steam supplied to the motor for controlling the motor.

43. An apparatus for generating steam in-
cluding in combination, a burner, a gen-
65 erator, a pump for supplying fuel to the burner, a pump for supplying water to the

generator, a steam motor for driving said pumps, said motor including a steam distributing valve and being in constant communication with a predetermined point in the generator, and means acting on said steam distributing valve and rendered operative by the variations in the pressure of the steam admitted to the motor for controlling the motor. 70

44. An apparatus for generating steam 75 including in combination, a burner, a generator, a pump for supplying fuel to the burner, a pump for supplying water to the generator, a steam motor for driving said pumps, said motor including a power cyl- 80 inder in normal communication with the generator and a valve for exhausting the steam from said cylinder, and means acting on the said exhaust valve and rendered operative by variations in the condition of 85 the steam in the generator for controlling said motor.

45. An apparatus for generating steam including in combination, a burner, a generator, a pump for supplying fuel to the 90 burner, a pump for supplying water to the generator, a steam motor for driving said pumps, said motor having a power cylinder normally in communication with the generator and a valve for exhausting the steam 95 from said cylinder; and means acting on said exhaust valve and rendered operative by variations in the pressure in the power cylinder for controlling said motor.

46. An apparatus for generating steam 100 including in combination, a burner, a generator having a continuous passage arranged to receive water at one end and to deliver steam at the other end, a pump for supply- 105 ing fuel to the burner, a pump for supply-
110 ing water to the generator, a steam motor for driving said pumps, said motor including a power cylinder in constant communication with a predetermined point in the generator and a valve for exhausting the steam from said cylinder, and means acting on said exhaust valve and rendered operative by variations in the pressure in the power cylinder for controlling said motor.

47. An apparatus for generating steam 115 including in combination, a burner, a generator having a continuous passage arranged to receive water at one end and to deliver steam at the other end, a pump for supply- 120 ing fuel to the burner, a pump for supply-
125 ing water to the generator, a steam motor for driving said pumps, said motor including a power cylinder normally in communication with that part of the generator in which the water is vaporized and a valve for exhausting the steam from said cylinder, and means acting on said exhaust valve and rendered operative by variations in the pressure in the power cylinder for controlling said motor. 130

48. An apparatus for generating steam including in combination, a burner, a generator, a pump for supplying fuel to the burner, a pump for supplying water to the generator, a steam motor for driving said pumps, said motor including a steam distributing valve and being in constant communication with the generator, means acting on said distributing valve and rendered operative by variations in one condition of the fluid in the generator for controlling said pump, and means rendered operative by variations in another condition of the fluid in the generator for varying the relation between the effective deliveries of said pumps.

49. An apparatus for generating steam including in combination, a burner, a generator having a continuous passage arranged to receive water at one end and to deliver steam at the other end, a pump for supplying fuel to the burner, a pump for supplying water to the generator, a steam motor for driving said pumps, said motor having a steam distributing valve and being in constant communication with said generator, means acting on said distributing valve and rendered operative by variations in the condition of the fluid at one point in the generator for controlling said motor, and means rendered operative by variations in the condition of the fluid at another point in the generator for varying the effective deliveries of said pumps.

50. An apparatus for generating steam including in combination, a burner, a generator having a continuous passage arranged to receive water at one end and to deliver steam at the other end, a pump for supplying fuel to the burner, a pump for supplying water to the generator, a steam motor for driving said pumps, said motor including a steam distributing valve and being in constant communication with a predetermined point in the generator passage, means acting on said distributing valve and rendered operative by variations in the pressure of the steam admitted to said pump for controlling said water, and means rendered operative by variations in the temperature at another point in the generator passage for varying the relation between the effective deliveries of said pumps.

51. An apparatus for generating steam including in combination, a burner, means for supplying fuel to the burner, a generator consisting of coiled pipe arranged with relation to said burner so that different parts of the generator are heated to different temperatures, a pump for supplying water to a cooler part of the generator, a steam motor for driving said pump, said motor including a steam distributing valve and being in constant communication with the generator, means acting on said distributing valve and rendered operative by variations in the

condition of the fluid at a hotter part of the generator for controlling said motor, and means for maintaining a predetermined relation between the supplies of fuel and water.

52. An apparatus for generating steam including in combination, a burner, means for supplying fuel to the burner, a generator consisting of coiled pipe arranged with relation to the burner so that different parts are heated to different temperatures, a pump for supplying water to a cooler part of the generator, a steam motor for driving said pump, said motor including a steam distributing valve and being in constant communication with the generator, means acting on said distributing valve and rendered operative by variations in the condition of the fluid at a hotter part of the generator for controlling said motor, means tending to maintain a predetermined relation between the supplies of fuel and water, and means for automatically varying the relation between said supplies.

53. An apparatus for generating steam including in combination, a burner, means for supplying fuel to the burner, a generator consisting of coiled pipe arranged with relation to the burner so that different parts are heated to different temperatures, a pump for supplying water to a cooler part of the generator, a steam motor for driving said pump, said motor including a steam distributing valve and being in constant communication with the generator, means acting on said distributing valve and rendered operative by variations in the condition of the fluid at a hotter part of the generator for controlling said motor, means tending to maintain a predetermined relation between the supplies of fuel and water, and means rendered operative by variations in another condition of the fluid in the generator for automatically varying the relation between the supplies of fuel and water.

54. An apparatus for generating steam including in combination, a burner, a pump for supplying fuel to the burner, a generator consisting of coiled pipe arranged with relation to the burner so that different parts are heated to different temperatures, a pump for supplying water to the generator, a steam motor for driving said pumps, said motor including a steam distributing valve and being in constant communication with the generator, means acting on said distributing valve and rendered operative by variations in the condition of the fluid at one point of the generator passage for controlling said motor, and means rendered operative by variations in the condition of the fluid at another point in the generator for varying the relation between the effective deliveries of the pumps.

55. An apparatus for generating steam including in combination, a burner, means for

- supplying fuel to the burner, a generator consisting of coiled pipe arranged with relation to the burner so that different parts of the generator are heated to different temperatures, a pump for supplying water to a cooler part of the generator, a steam motor for driving said pump, said motor including a steam distributing valve and being in constant communication with the generator, means acting on said distributing valve and rendered operative by variations in the pressure of the steam in a hotter part of the generator for controlling said motor, means tending to maintain a predetermined relation between the supplies of fuel and water, and means rendered operative by variations in the temperature at a cooler part of the generator for varying said predetermined relation.

56. An apparatus for generating superheated steam including in combination, a burner, means for supplying fuel to the burner, a generator consisting of coiled pipe arranged with relation to the burner so that the water is gradually heated, gradually vaporized, and then superheated, a pump for supplying water to the generator, a steam motor for driving said pump, said motor including a steam distributing valve and being in constant communication with said generator, means acting on said distributing valve and rendered operative by a slight range of variations in the pressure of the steam at or near that part of the generator where the water is vaporized for controlling the motor through a wide range of duty, means tending to maintain a predetermined relation between the supplies of fuel and water, and means rendered operative by variations in the temperature at a cooler part of the generator for varying said predetermined relation, whereby the effective supplies of fuel and water are varied in substantial unison with the variations of demand for steam energy and in substantially the same degree with said variations of demand.

57. An apparatus for generating superheated steam including in combination, a burner, a pump for supplying fuel to the burner, a generator consisting of coiled pipe arranged with relation to the burner so that the water is gradually heated, gradually vaporized, and then superheated, a pump for supplying water to the generator, a steam motor for driving said pump, said motor including a steam distributing valve and being in constant communication with said generator, means acting on said distributing valve and rendered operative by a slight range of variations in the pressure of the steam at or near that part of the generator where the water is vaporized for controlling the motor through a wide range of duty, and means rendered operative by variations in the temperature at a cooler part of the generator for varying said predetermined relation, whereby the effective supplies of fuel and water are varied in substantial unison with the variations of demand for steam energy and in substantially the same degree with said variations of demand.

58. An apparatus for generating superheated steam including in combination, a burner, a pump for supplying fuel to the burner, a generator consisting of coiled pipe arranged with relation to the burner so that the water is gradually heated, gradually vaporized, and then superheated, a pump for supplying water to the generator, a steam motor for driving said pump, said motor including a steam distributing valve and being in constant communication with that part of the generator at or near which the water is vaporized, means acting on said distributing valve and rendered operative by variations in the pressure of the steam admitted to the burner for controlling said motor, and means rendered operative by variations in the temperature at another part of the generator for varying the relation between the effective deliveries of said pumps, whereby the effective supplies of fuel and water are varied in substantial unison with the variations of demand for steam energy and in substantially the same degree with said variations of demand.

59. An apparatus for generating superheated steam including in combination, a burner, means for supplying fuel to the burner, a generator consisting of coiled pipe arranged with relation to the burner so that the water is gradually heated, gradually vaporized, and then superheated, a pump for supplying water to the generator, a steam motor for driving said pump connected with said generator, means rendered operative by a slight range of variations in the pressure in the generator for controlling said motor through a wide range of duty, means tending to maintain a predetermined relation between the supplies of fuel and water, and means rendered operative by variations in the temperature at a predetermined point in the generator for varying said predetermined relation, whereby the effective supplies of fuel and water are varied in substantial unison with the variations of demand for steam energy and in substantially the same degree with said variations of demand.

60. An apparatus for generating superheated steam including in combination, a burner, a pump for supplying fuel to the burner, a generator consisting of coiled pipe arranged with relation to the burner so that the water is gradually heated, gradually vaporized, and then superheated, a pump for supplying water to the generator, a steam motor for driving said pump, said motor including a steam distributing valve and being in constant communication with said generator, means acting on said distributing valve and rendered operative by a slight range of variations in the pressure of the steam at or near that part of the generator where the water is vaporized for controlling the motor through a wide range of duty, and means rendered operative by variations in the temperature at a cooler part of the generator for varying said predetermined relation, whereby the effective supplies of fuel and water are varied in substantial unison with the variations of demand for steam energy and in substantially the same degree with said variations of demand.

motor connected with the generator for driving said pumps, means rendered operative by a slight range of variations in the pressure of the steam at or near that part of the generator where the water is vaporized for controlling said motor through a wide range of duty, and means rendered operative by variations in the temperature at a pre-determined part of the generator for controlling the effective delivery of the fuel pump, whereby the effective supplies of the

fuel and water are varied in substantial union with the variations of demand for steam energy and in substantially the same degree with said variations of demand.

15

In testimony whereof, I have signed my name to this specification, in the presence of two subscribing witnesses.

EDWARD C. NEWCOMB.
